(57) **CLAIM**

The ornamental design for a jig for repairing broken mounting studs, as shown and described.

DESCRIPTION

FIG. 1 is a top perspective view of a jig for repairing broken mounting studs showing my design;

FIG. 2 is a top plan view thereof;

FIG. 3 is a side elevation view thereof;

FIG. 4 is an opposite side elevation view thereof;

FIG. 5 is a bottom plan view thereof;

FIG. 6 is an end elevation view thereof; and,

FIG. 7 is an opposite end elevation view thereof.

The broken lines in the drawings illustrate portions of the jig for repairing broken mounting studs and form no part of the claimed design.

1 Claim, 3 Drawing Sheets
